GLASS CUTTER

Arthur Terry Fletcher, Bristol, Conn.

Application September 9, 1940, Serial No. 356,026

21 Claims. (Cl. 49—52)

My invention relates to glass cutters.

It has among its objects to provide an improved glass cutter. Further objects are to provide an improved cutter unit for such cutters and such a unit having improved means for positioning and holding the same in a suitable holder or support. Still another object is to provide an improved holder or support cooperating with my improved unit in an improved manner. Still further objects of my invention are to provide such an improved cutter unit and improved holder or supporting means which are adapted to use in either ordinary hand operated cutters or in the pillar posts of glass cutting machines. These and other objects and advantages of my improved construction will, however, hereinafter more fully appear.

In the accompanying drawing, I have shown for purposes of illustration certain embodiments which my invention may assume in practice.

In the drawing—

Figure 1 is a top plan view of a hand-operated cutter equipped with my improvements;

Fig. 2 is a side elevation of the same;

Fig. 3 is an enlarged perspective view showing the parts of my improved cutter unit in spaced relation ready for assembly;

Fig. 3a is a side elevation of the tip part of the unit shown in Figure 3 on a smaller scale;

Fig. 4 is a perspective view similar to Figure 3 but showing the parts when in assembled relation;

Fig. 4a is a side elevation of the unit shown in Figure 4 on the scale of Figure 3a;

Fig. 5 is a perspective view of the working end of a holder having my improved unit in operative position thereon, one end of the cooperating tool being shown in dotted lines in the position occupied thereby in inserting or removing the unit;

Fig. 6 is a like perspective view showing the unit spaced from the end of the holder, the tool being also indicated in dotted lines in position in the unit;

Fig. 7 is a side elevation of the tool;

Fig. 8 is a vertical sectional view of a plurality of my improved units in feeding relation in a pillar post of a glass cutting machine, and

Fig. 9 is a transverse sectional view on line 9—9 of Figure 8, the scale being enlarged.

In the illustrative construction shown in Figures 1 to 6, I have shown a usual holder 1, adapted to be grasped in the hand, and having my improved glass cutting unit, generally indicated at 2, removably carried in its working end;

this unit and the working end of the holder being of an improved construction and being adapted to enable the use of an improved unit inserting and removing tool, generally indicated at 3, all as hereinafter more fully described.

Referring more particularly to the unit 2, it will be observed that the same includes a wheel carrying wire clip or so-called "tip" 4 and a cooperating frame 5, each of which is of improved construction and operatively connected in an improved manner to the other, to form the improved unit 2. As shown, a cutter wheel 6 of usual construction is journaled on a cross portion 7 of a U-shaped wire clip or tip having longitudinally extending wire side portions 8 extending rearwardly from this cross portion and these portions 8 suitably angularly off-set relative to one another as shown, for example, in Figure 3a. The frame 5 is also U-shaped, but formed of sheet metal and of such maximum width as to fit snugly between the portions 8 while permitting the wheel to rotate freely in the open end of the frame. The frame is also disposed with its open end toward the cross portion 7 of the tip 4, and is provided with opposite longitudinal slots 9 in its end adjacent the latter, which are adapted to project between the wheel 6 and side portions 8, and receive the cross portion 7 on opposite sides of the wheel 6. Further, the opposite or closed end of the frame 5 is provided with a transverse slot 10 of sufficient width to receive the angularly off-set extremities 11 of the side portions 8 (Figure 4a), and in which these extremities are bent laterally when the U-shaped tip has been assembled with its cross portion 7 engaging the ends of the slots 9; the tip 4 with the wheel 6 thereon preferably being formed initially as shown in Figure 3, i. e., with its portions 8 angularly disposed, and thereafter having these portions bent flat into contact with the sides 12 of the frame 5 and their extremities 11 bent into the slot 10, as shown in Figure 4.

As a result of this construction, the wire tip 4 and frame 5 not only cooperate to prevent longitudinal movement of either relative to the other, but each cooperates to brace the other, in such manner as to produce a construction which provides an effective journal for the wheel 6 without causing binding thereof. Further, it will be noted that both the frame 5 and the side portions 8 of the tip 4 provide effective longitudinally extending guiding portions which may be very accurately formed and which are, accordingly, adapted to cooperate in positioning the

unit in a suitable support, all while the construction remains exceedingly inexpensive. Of these, however, I rely upon the off-set portions 8 to hold the unit against dropping out of grooves in the holder, the off-set relation of these portions to one another enabling them to engage opposite walls of opposite grooves with sufficient friction to prevent the unit from dropping out of the grooves, as hereinafter described. Attention is also directed to the fact that an unobstructed vertical space 13 is provided between the wheel 6 and the closed end of the frame 5, in such manner as to receive a corresponding straight portion 14 on a new and convenient unit handling tool 3, the use of which markedly facilitates the handling, insertion and removal of the very small unit 2.

Referring to the holder 1, it will be observed that the latter is provided with a transverse or vertical slot 16 in its front or working end and with longitudinal or horizontal slots 17 in its opposite longitudinal sides and which open into the slot 16 near its top and lead through the front edges of the walls of the slot 16 near the junction of the sloping end 1a, 1b of the holder. Of these slots, the slot 16 is adapted to receive the unit 2 when inserted longitudinally therein with the portions 8 opposite the slots 17, while these slots 17 are adapted to deflect and frictionally engage the off-set side portions 8 when the unit is thus longitudinally inserted; the closed end 18 of frame 5 also abutting against the closed vertical end 19 of the slot 16 when the cutter wheel 6 is in cutting position at the front end of the holder as illustrated in Figures 1, 2 and 5. Here, attention is also directed to the fact that the unit 2 is thus very securely positioned frictionally in the holder by the friction of the portions 8 against opposite upper and lower side surfaces of opposite slots 17 by the different off-set portions 8, all without requiring the provision of any additional spring means and without requiring any means either on the holder or on the unit which extend beyond the inner wall of the slot 16. Further, the cutter wheel is the only protruding portion of the unit, the frame 5 and portions 8 being wholly within the limits of the slots 16 and 17, so that there are no projections. Moreover, it will be observed that the structure of the holder is such as to facilitate deft handling of the tiny unit with a tool, as distinguished from markedly more clumsily with the fingers; the slot 16 extending clear through the holder transversely, in such manner as to enable the tool 3 to be received when its portion 14 is projected through the opening 13 in the unit from either the top or bottom, and also enabling this portion to be projected through this aperture to any desired extent without conflicting with the holder. Thus, obviously, the unit may be assembled in the holder with the parts in the relation shown in Figure 6, and, when assembled, the parts may be separated when in the position shown in Figure 5, while, if desired, the same may also be assembled or separated by inserting the tool from beneath the unit.

In Figures 8 and 9, I have shown a series of my improved units 2 in superimposed vertical feeding relation in an elongated magazine or chamber 20 in a support in the form of a pillar post 21 of a machine cutter. In this construction, the units and their cooperating slots in the support are essentially similar to the construction previously described. Here, however, the

several units 2 are disposed in superimposed relation in chamber 20, herein rectangular and corresponding to the slot 16, while the opposite off-set side portions 8 on the units 2 are deflected and act as heretofore frictionally on opposite walls of opposite slots 22 in that chamber at right angles to the latter and corresponding to the slot 17. Obviously, with the portions 8 of the units frictionally engaging opposite walls of opposite slots 22, and the latter tending to hold the units frictionally in the relation shown in Figure 8 and each unit having its wheel 6 at the bottom, the units may be fed downward successively into their bottommost or operative position at the open end of the chamber 20, while being guided in the downward movement and held frictionally in any position in the post, including this operative position. Here note also that a suitable abutment is also provided, as, for example, a screw 23 rotatable in a threaded aperture 24 and having flats 25, the bottom one of which engages the top of the top unit and thereby holds all the units against longitudinal upward movement in the chamber 20 when the bottommost wheel is being pressed against the work during cutting, without spoiling the threads of screw 23. It will be understood that whenever it is desired to eject the bottommost unit, as, for example, when it is dull, the screw 23 is withdrawn and a new unit 2 is pressed down from the top in such manner as thereby to cause the bottommost unit to be ejected and the next unit above the same to be moved down into operative position, whereupon the screw 23 is again inserted.

As a result of my improved construction, my improved unit is adapted to be very securely held in position in the support by the portions 8 without requiring the use of any additional holding springs. My improved support also cooperates effectively in holding the units while also enabling the unit to be very readily inserted or removed. Further, attention is also directed to the minimum amount of material and minimum number of parts, and further to the minimum number of operations required to produce my improved construction, which enables the latter to be very inexpensively manufactured, both as regards the unit and the holder. It is also made possible, due to the definite positioning of the unit in the support, to reduce the wear on both the unit and support, while any loss of effectiveness due to fatigue of the metal is minimized. Moreover, my improved construction is very convenient in use and adapted to cooperate in an improved manner with a handling tool, and to be very deftly handled and markedly more quickly inserted and removed with such a tool, than is possible with the fingers. On the other hand, if a special tool is not available, a knife will serve admirably, the unit being securely positioned on the point of any small blade inserted in the position indicated for the tool end 14 and such a blade being adapted to be slipped between the wheel and the adjacent side of the frame 5. All need for projecting journals or the like, on which the hands are apt to be injured, is also eliminated at the same time that all need for sets of cross slots cooperating with such protruding ends or for additional material projecting beyond the vertical groove in the holder is eliminated. My improved unit and my improved cooperating receiving and guiding means therefor is also equally well adapted to use in hand-manipulated cutters and in the pillar posts of glass cutting machines, and my

improved unit may thus be positioned and fed in a magazine in a wholly new manner. These and other advantages of my improvements will, however, be clearly apparent to those skilled in the art.

While I have in this application specifically described certain embodiments which my invention may assume in practice, it will be understood that the same are shown for purposes of illustration and that my invention may be modified and embodied in various other forms without departing from its spirit or the scope of the appended claims.

What I claim as new and desire to secure by Letters Patent is:

1. In a glass cutter unit, a frame having longitudinal sides and having a cutter wheel journaled in one end of said frame, and also having outer longitudinal guides carried by said frame on opposite sides thereof and on outer faces of said longitudinal sides and projecting laterally from and extending along said opposite sides of said frame.
2. In a glass cutter unit, a frame having longitudinal sides and having a cutter wheel journaled in one end of said frame, and also having resilient longitudinal guides projecting laterally from and extending along opposite outer sides of said frame, the sides of said frame also having edge portions above and below said guides.
3. In a glass cutter unit, a frame having longitudinal sides and an open end, and a cooperating member carried on said frame and having a cutter wheel journaled on said member and rotatable in the open end of said frame and having longitudinal guides angularly off-set relative to one another, and also extending along outside opposite outer sides of said frame.
4. In a glass cutter unit insertable in a holder, a U-shaped frame, and a cooperating reversely disposed U-shaped member fixed thereto and having a cutter wheel journaled on the closed end of said member and rotatable in the open end of said frame, and also having outer longitudinal guides extending along outside opposite sides of said frame.
5. In a glass cutter unit insertable in a holder, a U-shaped frame, and a cooperating reversely disposed U-shaped member having a cutter wheel journaled thereon in the open end of said frame, and also having outer longitudinal guides extending along outside opposite sides of said frame, said U-shaped frame being sheet metal and said U-shaped member comprising a wire clip having spaced side portions carried on said frame.
6. In a glass cutter unit insertable in a holder, a frame having longitudinally extending sides and an open end, and a cooperating member having a cutter wheel journaled thereon and rotatable in the open end of said frame, said cooperating member having outer longitudinal guides extending along outside opposite sides of said frame, and said frame having slots in its open end and said cooperating member also having a transverse wheel carrying portion between said longitudinal guides and engaging in the ends of said slots.
7. In a glass cutter unit insertable in a holder, a U-shaped frame, and a cooperating member having a cutter wheel journaled thereon and rotatable in the open end of said frame, and also having outer longitudinal guides extending along outside opposite sides of said frame, said frame having slots in its closed end and said longitudinal guides comprising wire sections having their rear ends bent into said slots.
8. In a glass cutter unit insertable in a holder, a U-shaped frame, and a cooperating member having a cutter wheel journaled thereon and rotatable in the open end of said frame, and also having outer longitudinal guides extending along outside opposite sides of said frame, said frame having slots in its front and rear ends and said guides comprising longitudinal wire sections extending into said slots at their opposite ends.
9. In a glass cutter unit insertable in a holder, a U-shaped frame having a slotted open end, and a U-shaped wire clip fixed to said frame and having a transverse journal portion carrying a cutting wheel and disposed in the slots in the open end of said frame and also having longitudinal relatively angularly off-set side portions outside the sides of said frame.
10. In a glass cutter unit insertable in a holder, a U-shaped frame having slotted closed and open ends, and a U-shaped wire clip having a transverse journal portion carrying a cutting wheel and disposed in the slots in the open end of said frame and also having longitudinally extending side portions extending along outside the sides of said frame and having ends bent into the slots in the closed end thereof.
11. In a glass cutter, a support having a passage open in one direction to receive a cutting unit and also having open ended grooves opening in said direction to receive unit guides and in opposite walls of said passage, and a cutter unit having a frame received in said passage and also having guides projecting laterally from said frame and received in said grooves and extending longitudinally of said frame outside the latter, and a cutter wheel journaled on said frame between opposite sides thereof and at one end of said guides.
12. In a glass cutter, a transversely slotted support having opposite longitudinally extending slots therein, and a cutter unit having a frame in the transverse slot in said support, a transverse journal at the outer end of said frame, angularly off-set longitudinally extending guiding portions projecting laterally from said frame and disposed in the longitudinal slots in said support, and a cutter wheel on said journal, said portions being deflected by and engaging in said longitudinal slots to restrain said unit against unintentional movement relative thereto.
13. In a glass cutter, a transversely apertured and longitudinally grooved support having an inner end wall in the transverse aperture therein, and a cutter carrying unit in the transverse aperture therein having guides insertable and removable longitudinally in the longitudinal grooves in said support and carrying a cutter wheel at its front end and having a closed inner end engaging the inner end wall of the transverse aperture in said support and also having a transverse aperture between said wheel and said closed end.
14. In a glass cutter, a transversely apertured and longitudinally slotted support having an inner end wall in the transverse aperture therein, and a cutter carrying unit in the transverse aperture therein having guides insertable and removable longitudinally in the longitudinal slots in said support and carrying a cutter wheel at its front end and having a closed inner end engaging the inner end wall of the transverse aperture in said support and also having a trans-

verse aperture between said wheel and said closed end, said transverse aperture in said support comprising a slot having said longitudinal slots in its side walls and open at its opposite ends and providing access for a tool to the transverse aperture in said unit from said opposite ends.

15. In a glass cutter, a transversely apertured and longitudinally grooved support having an inner end wall in the transverse aperture therein, and a cutter carrying unit in the transverse aperture therein having guides insertable and removable longitudinally in the longitudinal grooves in said support and carrying a cutter wheel at its front end and having a closed inner end engaging the inner end wall of the transverse aperture in said support and also having a transverse aperture between said wheel and said closed end, said guides being relatively angularly offset and engageable with and deflected by the walls of said longitudinal grooves to retain said unit in position in said support.

16. In a glass cutter, a post having an elongated chamber therein having an open end, a series of cutter units in superimposed position in said chamber, and cooperating unit guiding and positioning means for enabling said units to be successively fed through said chamber to said open end and successively maintained in operative position in said open end.

17. In a glass cutter, a post having an elongated chamber therein having an open end and grooves in opposite walls of said chamber, and a series of superimposed cutter units in said chamber and successively movable through the latter into an operative position in said open end and each having guiding and positioning means cooperating with said grooves and a cutter wheel at the same end of each unit.

18. In a glass cutter, a post having an elongated chamber therein having an open end and grooves in opposite walls of said chamber, and a series of superimposed cutter units in said

chamber and successively movable through the latter into operative position in said open end and each having guiding and positioning means cooperating with said grooves and a cutter wheel at the same end of each unit, and means acting on the units in said chamber for preventing movement of the same in one direction longitudinally in said chamber.

19. In a glass cutter, a pillar post having a longitudinal chamber adapted to receive a plurality of cutter units in superimposed position therein and having an open end in which the bottommost unit is disposable in operative position, and also having longitudinal slots on opposite walls of said chamber leading to said open end and adapted to receive guide portions on said superimposed units and successively direct the latter into said operative position as said units are fed longitudinally through said chamber.

20. In a glass cutter, a pillar post having a longitudinal chamber adapted to receive a plurality of cutter units in superimposed position therein and having an open end in which the bottommost unit is disposable in operative position, and also having longitudinal slots on opposite walls of said chamber leading to said open end and adapted to receive guide portions on said superimposed units and successively direct the latter into said operative position as said units are fed longitudinally through said chamber, said chamber also having a transverse aperture therein and unit positioning means adjustable in said aperture.

21. In a glass cutter, a support having a vertical slot in its forward end and longitudinal horizontal slots intersecting the vertical slot and extended rearwardly past the vertical slot, and a cutter unit comprising an axled cutter located in the vertical slot and a cutter carrier engaged in the horizontal slots.

ARTHUR TERRY FLETCHER.
